UNITED STATES PATENT OFFICE

JAMES BEVERIDGE, OF BROOKLYN, NEW YORK.

BUCKLE.

SPECIFICATION forming part of Letters Patent No. 715,948, dated December 16, 1902.

Application filed August 16, 1902. Serial No. 119,871. (No model.)

To all whom it may concern:

Be it known that I, JAMES BEVERIDGE, a citizen of the United States of America, and a resident of New York, borough of Brooklyn, 5 and State of New York, have invented certain new and useful Improvements in Buckles, of which the following is a specification.

This invention relates to buckles or clasps for securing straps for trunks, luggage-carriers, and mail-pouches and other packages or bundles which it is desired to secure safely and reliably.

The particular class of buckles to which the present invention relates is that now universally adopted by the United States Government for the use of letter-carriers in securing bundles of mail-matter.

Heretofore buckles of the described class have been made with a spring-actuated grip 20 jaw or tongue; but the spring is not always to be depended upon, and sometimes the strap slips through the buckle at times when it is highly important that the strap be held firmly and securely.

It is the object of the present invention to apply positive supplemental pressure to the grip-jaw, the spring-pressure on the grip-jaw being used during adjustment of the strap for securing the same until the supplemental 30 pressure is applied, and then the grip-jaw does not have to rely on the spring-pressure for positively securing the strap.

A further object is to apply pressure between the pivot and the active end of the 35 grip-jaw.

The additional positive pressure on the grip-jaw may be obtained in several ways, and those which are preferred will be described.

In the accompanying drawings, Figure 1 is a 40 perspective view of the preferred form of my improved buckle open and partly broken away. Fig. 2 is a longitudinal sectional view of the buckle, showing it locked in use. Fig. 3 is a detached perspective view of the grip-jaw clencher, which, in connection with a padlock or other suitable locking means, forms the medium of supplemental pressure of the 45 preferred form of the invention. Fig. 4 is a longitudinal section of a modified form of the 50 buckle in which the hasp of an ordinary padlock serves as the supplemental pressure medium for the grip-jaw. Fig. 5 is a side ele-

vation of another modification in which the grip-jaw is pressed in by the hasp of the padlock, and Fig. 6 is an end view of the same. 55

Referring to the drawings, Figs. 1, 2, and 3, A indicates the frame of a buckle, and B the grip-jaw thereof. The frame is appropriately made of cast metal, having a loop C, formed with a cross-bar D, to which the end 60 of a trunk or other strap E is applied. The loop C has a keeper F, through which the loose end of the strap after it has been made fast may be passed. Shank a of the frame A bears at one end the loop C and at the other 65 end a transverse elongated eye G, through which the free end of the strap is to be passed, so as to be secured by the grip-jaw B, which forms a bight in the strap and acts to hold the strap firmer the greater the outward pull 70 on the strap. Grip-jaw B is pivotally mounted on the frame by a pivot-pin b, which passes through the shank b' of the grip-jaw and turns in ears or lugs a' on the shank of the buckle-frame. A finger-piece b² at the outer 75 end of the jaw-shank b' serves to move the preferably serrated grip-jaw B out of the eye G against the tendency of a spring H to press the grip-jaw into the eye. The eye G has a loop extension I, the cross-bar i of which 80 serves as a pivot for a grip-jaw clencher J, composed, preferably, of a strip of heavy sheet metal which is doubled and formed with a sleeve j for the pivot i. One portion of the grip-jaw clencher J has a bearing-surface J' and an intermediate nose J², bent toward the grip-jaw and away from the other portion j' of the clencher, which portion j' is longer than the nose portion J' J² and has at its free end a transverse opening j². Loop C 85 bears an eye K, onto which the open end of the grip-jaw clencher may be engaged, while the hasp l of a padlock L is passed through the eye to secure the clencher. 90

A buckle such as described is well adapted 95 for trunk-straps, although it may be used with other straps, if desired, and it is used and operates as follows: The free end of the strap is passed, as usual, through the eye G and over the grip-jaw, it being drawn as tight 100 as possible. The spring serves to press the grip-jaw into the eye and to form a bight in the strap, as usual, the outward strain on the strap serving to operate the grip-jaw to draw

it forcibly upon the strap. The end of the strap is then passed through the end of the keeper C. To give the supplemental pressure on the grip-jaw, which is additional to that imparted by the spring H, the grip-jaw clencher is moved from open position (shown in Fig. 1) to closed position of Fig. 2 and its opening J^2 caused to receive the eye K. This presses the hasp portion of the clencher 5 against the bearing-surface J' and in turn presses the nose J^2 hard against the strap, which forces the grip-jaw positively and more forcibly against the portion of the strap passing through eye G. When the hasp of the 10 padlock is passed through the eye K and over the hasp portion of the clencher, the latter is secured and cannot spring back out of its described engagement. The hasp of the padlock being then snapped into its lock, the 15 grip-jaw is locked down hard and the strap sealed or secured against unauthorized tampering. What may be termed a "lock-buckle" is formed.

In Fig. 4 a simple lock-buckle is shown, the 20 frame M and grip-jaw M' being shaped, however, so as to form, as before, a bight in a strap. The grip-jaw clencher as a special member is dispensed with, and the hasp of a padlock N takes its place. There the frame 25 of the buckle is formed with a laterally-extending eye O, through which the grip-jaw extends, and the eye is of sufficient size to permit the insertion of the hasp of the padlock therethrough, which hasp fills the eye and wedges or presses upon the grip-jaw.

In Figs. 5 and 6 the buckle-frame P is formed with two side lugs Q, to which the grip-jaw R is pivoted at q, so that it is located between the lugs. Eyes q' are formed 30 on the lugs, and through these the hasp of a padlock S is passed transversely to the buckle-frame, so as to positively press upon the grip-jaw. In the modifications shown the padlock is caused to stand out from the buckle. This 35 is desirable for mail-pouches.

Preferably the pressure on the grip-jaw occurs between its pivot and toe; but the invention is not limited to this nor to the precise details shown.

40 50 What I claim as new and of my invention is—

1. In a buckle, the combination of a frame, a spring-actuated grip-jaw, between which

and the frame a strap may be secured by the grip-jaw, and supplemental pressure means 55 acting on the grip-jaw, substantially as described.

2. In a buckle, the combination of a frame provided with an eye for a strap, a pivoted grip-jaw the gripping end of which extends 60 into and coöperates with the eye to secure a strap, and means for positively pressing on the grip-jaw between its pivot and said eye to force it toward the eye, substantially as described. 65

3. In a buckle, the combination of a frame, a spring-actuated grip-jaw, a clencher free from the grip-jaw, and means for locking the clencher to abut upon the grip-jaw, substantially as described. 70

4. In a buckle, the combination of a frame, a spring-actuated grip-jaw, a pivoted grip-jaw clencher free from the grip-jaw, and means for locking the clencher upon the grip-jaw, substantially as described. 75

5. In a buckle, the combination of a frame, a grip-jaw, and a positively-operated grip-jaw clencher to abut upon the grip-jaw, substantially as described. 80

6. In a buckle, the combination of a frame, a grip-jaw, a grip-jaw clencher free from the grip-jaw provided with a hasp, a hasp-engaging eye on the frame, and means for locking the hasp to said eye, substantially as described. 85

7. In a buckle, the combination of a frame, a grip-jaw, a pivoted grip-jaw clencher provided with a nose to bear on the grip-jaw, and means for locking the clencher upon the grip-jaw, substantially as described. 90

8. In a buckle, the combination of a frame, a grip-jaw, a grip-jaw clencher pivoted to one end of the frame, and means at the other end of the frame for locking the clencher upon the grip-jaw, substantially as described. 95

9. In a buckle, the combination of two members adapted to engage and bind a strap between them, and means independent of and for locking the two members upon the strap, substantially as described. 100

Signed at New York, N. Y., this 14th day of August, 1902.

JAMES BEVERIDGE.
